UNITED STATES PATENT OFFICE.

JOHN R. HUME, OF CHICAGO, ILLINOIS.

STREET INDICATOR.

Application filed September 8, 1919. Serial No. 322,509.

To all whom it may concern:

Be it known that I, JOHN R. HUME, a citizen of the United States, and a resident of the city of Chicago, county of Cook, and 5 State of Illinois, have invented certain new and useful Improvements in Street Indicators, of which the following is a specification.

My invention relates to improvements in 10 street indicators for use on street cars and the like, and has for its object the provision of an improved construction of this character which is of simple construction and highly efficient in use.

15 Other objects will appear hereinafter.

My invention consists in the combinations and arrangements of parts hereinafter described and claimed.

The invention will be best understood by 20 reference to the accompanying drawings forming a part of this specification, and in which,

Fig. 1 is a longitudinal section of a street car equipped with street indicating means 25 embodying the invention.

Fig. 2 a top plan view showing the arrangement of shafts for operating the same.

Fig. 3 a transverse section of the shaft arrangement.

30 Fig. 4 an enlarged vertical section of one of two indicator casings mounted in the car.

Fig. 5 a face view corresponding with Fig. 4.

35 Fig. 6 a section taken on line 6-6 of Fig. 4 and

Fig. 7 a detailed view of a gearing arrangement in the car.

The preferred form of construction as 40 illustrated in the drawings comprises two sign casings 8 arranged at each end of the car and each provided with a glass front 9 giving a view to the interior by occupants of the car. Each of the casings 8 is provided

45 with a transverse driving shaft 10 connected by a worm drive with a longitudinal driving shaft 10' as best shown in Figs. 1 and 7. Each of the shafts 10' is operatively connected with a parallel shaft 11 by means of 50 gears 12 and idler shafts 13 and 14 are arranged in the lower portions of each of said casings 8 as shown. Shafts 10' and 13 carry cooperating driving pulleys or drums 15 and shafts 11 and 14 carry co-operating driving pulleys or drums 16 as shown. An endless 55 belt 17 is arranged to travel over drums 15

and another endless belt 18 is arranged to travel over drums 16. The belt 17 carries projections or blades 19 and the belt 18 carries corresponding projections or blades 20. 60 One portion of the belt 17 is arranged to travel over a substantial semi-cylindrical guide 21, the other portion thereof being arranged to travel vertically immediately to the rear of suitable guides 22 along the side 65 walls of the casing 8. Likewise a portion of the belt 18 is arranged to travel over the semi-cylindrical guide 23 and the edges of the other portion of the belt 18 are arranged to travel over curved guides 24 projecting 70 from opposite sides of the side walls of the casing 8, the blades or projections 20 traveling between the sign members as indicated in Figs. 4 and 6.

75 Sign members 25 are arranged to travel in each of the casings 8 to be viewed through the corresponding glass front 9, said sign members resting between the blades or projections 19 and 20 and being carried thereby during one portion of their travel as shown. 80 Each of the sign members 25 carries a transverse pin 26 adapted to travel in the guides 22 as indicated, and each glass plate 9 is outwardly bulged at 27 to permit of turning 85 or reversal of each of the sign members. 85

By this arrangement it will be observed that upon operation of the shaft 10 the sign members 25 will be forced to travel in their casings and will be successively brought to the upper end of the guides 22 when they 90 will fall outwardly through said guides automatically reversing in such falling and exposing one of their sides at the top and the reverse side at the bottom. Each sign member, after reversal within the bulged 95 portion 27 slides downward completely out of engagement with the belts 17 and 18, being controlled in this movement by engagement between the transverse pins 26 and the guide 22. At the bottom of the casing 8, 100 each sign member is directed by the guide 22 again into the control of the belts 17 and 18. The faces of the sign members 25 exposed at the top of the casing carry the numbers or names of the streets and the reverse sides of said sign members carry suitable advertisements or other desirable matter. The shaft 10 carries gears 28 meshing with loose gears 28' on the motor shafts of 105 electric motors 29, said gears 28' being adapted to be connected by spring operated clutch members 30 of any approved type 110

with the said motor shafts for driving said gears. The motor 29 is connected in series with the motor of the car (not shown) and is operative therewith, both motors being controlled by the motor controller of the car and hence it will be seen that the speed of the motors are constant at all times. Each of the clutch members 30 is operatively connected with a lever 31, operatively connected by means of a link 32 with a lever 33 mounted at the upper end of the electric car. Suitable cam members 34 are arranged at suitable intervals on the trolley wire 35 to engage the levers 33 as indicated in Fig. 1 to throw into operation the corresponding clutches 30 against the action of the clutch springs as will be readily understood. Operation of either of the clutches 30 correspondingly operates the corresponding sign members 25 to indicate the next succeeding stop of the car as will be readily understood. Each of the sign casings 8 contains sufficient sign members 25 to indicate in duplicate the various street crossings or stops arranged in reversely arranged sets to provide for travel of the car in opposite directions as will be readily understood. By this arrangement it will be observed that the various street crossings will be automatically exhibited through each of the casings 8, one of the trolley poles being utilized for travel of the car in one direction and the other trolley pole being utilized for travel of the car in the opposite direction. The shaft 10 is also operatively connected by means of sprocket chains 36 with shafts 37 positioned on the sides of the car. Each of the shafts 37 carries a plurality of driving drums 38 cooperating with corresponding sign belts 39 and idler drums 40 as indicated in Figs. 1 and 3. The belts 39 are also provided with duplicate sets of reversely arranged names of the cross streets and indicators 41 are properly positioned on the sides of the car to indicate the next stop. By this arrangement it will be observed that the various cross streets or stops of the car will also be indicated on the side walls thereof between the seats.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent, is:

1. The combination with a car and track therefor, of a plurality of traveling sign elements mounted thereon; means for operat-

ing said sign elements; a motor for operating said operating means; an operative connection between said motor and said operating means, including a clutch; means carried by said car for operating said clutch; and stationary elements positioned along the car track and arranged to operate said clutch operating means, substantially as described. 70

2. The combination with a car and track therefor, of a plurality of traveling sign elements mounted thereon; means for operating said sign elements; a motor for operating said operating means; an operative connection between said motor and said operating means including an automatically releasing spring-held clutch; means carried by said car for operating said clutch; and stationary cam elements positioned along the car tracks and arranged to operate said clutch operating means, substantially as described. 75

3. The combination with an electric car and track therefor, of a trolley pole on said car; a plurality of reversible traveling signs mounted on said car; traveling belts for operating said signs; a motor for operating said belts; an operative connection between said motor and belts, including a clutch; means carried by said trolley pole for operating said clutch; and stationary elements positioned along the car track and arranged to operate said clutch operating means, substantially as described. 90

4. The combination with an electric car and track therefor, of a trolley pole on said car; a plurality of reversible traveling signs mounted on said car; traveling belts for operating said signs; a motor for operating said belts; an operative connection between said motor and signs, including an automatic releasing spring-held clutch; means carried by said trolley for operating said clutch; and stationary cam elements positioned along the car track and arranged to operate said clutch operating means, substantially as described. 100 105

5. A street indicator comprising in combination with a casing having an opening therein, of a plurality of signs in said casing adapted to pass said opening; continuous belts mounted to travel in said casing, there being projections on said belts for engagement with said signs; and means for operating said belts, said means including a clutch, a motor, a lever operatively connected to said clutch, and stationary elements for actuating said lever, substantially as described. 115 120

6. A street indicator comprising in combination with a casing having an opening therein, of a plurality of reversible signs in said casing adapted to pass said opening; semi-cylindrical guide members in said casing; belts mounted to travel around said guide members; means on said belts for en- 125 130

gagement with said signs; and means for operating said belts, said means including a clutch, a motor, a lever operatively connected to said clutch, and stationary elements for actuating said lever, substantially as described.

7. A street indicator, comprising in combination with a car and a track therefor, of a casing in said car having an opening 10 formed therein; a plurality of signs in said casing adapted to pass said opening; continuous belts mounted to travel in said casing, there being projections on said belt for engagement with said signs; a clutch for controlling the operation of said belts; means for operating said clutch; and means comprising cam members suspended from a trolley line in the path of said car and a lever carried by the trolley pole of said car and 15 connected to said clutch for actuating said clutch operating means, substantially as described.

8. A street indicator comprising in combination with a casing having an opening 20 formed therein, of a plurality of reversible signs in said casing adapted to pass said opening there being transverse pins carried by said signs; semicylindrical guide members arranged in said casing in spaced relation with respect to each other; belts passing 25 over each of said guide members, there

being projections on said belts for engagement with said signs; means for operating said belts; and vertically extending guides 35 on opposite sides of said opening for the reception of the transverse pins carried by said signs when said signs pass said opening, substantially as described.

9. A street indicator comprising in combination with a casing having an opening 40 therein, of a plurality of signs in said casing adapted to pass said opening; belts arranged in said casing in spaced relation with respect to each other, a portion of one of said belts being adapted to travel in substantially a semicircular plane and the other portion of said belt being adapted to travel in substantially a vertical plane, there being projections on said belts for engagement with said signs; means for operating said belts; a vertically 45 extending guide in said casing in spaced relation with respect to the vertical portion of said belt arranged and adapted to guide said signs past said opening, substantially as described.

In testimony whereof I have signed my name to this specification in the presence of two subscribing witnesses.

JOHN R. HUME.
